UNITED STATES PATENT OFFICE.

JOHN STARK, OF CHESTER, PENNSYLVANIA.

HYDROCARBON-BURNER.

1,360,595.

Specification of Letters Patent. Patented Nov. 30, 1920.

Application filed December 3, 1919. Serial No. 342,135.

To all whom it may concern:

Be it known that I, JOHN STARK, a citizen of the United States, and a resident of Chester, in the county of Delaware and State 5 of Pennsylvania, have invented a certain new and useful Improvement in Hydrocarbon-Burners, of which improvement the following is a specification.

My invention relates to means for utilizing hydrocarbon liquids as fuel in furnaces of the various known types, and its object is to provide an appliance of such character, in the operation of which the constituent molecules of steam may be vaporized into 15 their constituents of hydrogen and oxygen, and combined with vaporized molecules of hydrocarbon liquid, and the resultant gas be projected into a furnace chamber, in such manner as to effectively and economically 20 exert and maintain a high degree of heat therein.

The improvement claimed is hereinafter fully set forth:

In the accompanying drawings: Figure 1, 25 is a section, through a portion of an end wall of a furnace, with the appliance of my invention shown in elevation; Fig. 2, a plan view of the appliance; Fig. 3, a side view, partly in section, of the same; Fig. 4, a transverse section, on the line 4—4 of Fig. 3; Fig. 30 5, a partial longitudinal section, on an enlarged scale, through the hydrocarbon tube; Fig. 6, a partial axial section, illustrating a structural modification of the appliance; Fig. 35 7, a partial axial section, on an enlarged scale, showing one form of the ejection nozzle; Fig. 8, a transverse section through the same; Fig. 9, a partial axial section, showing another form of ejection nozzle; and, 40 Fig. 10, an end view of the same.

In the practice of my invention, referring descriptively to the specific embodiment thereof which is herein exemplified, and premising that it is not limited in application to any particular form of furnace or heating chamber, I provide an inner hydrocarbon tube, 1, leading from a source of supply of hydrocarbon liquid, and an encircling outer vaporizing tube, 2, each of which is 45 connected, at one end, to a block or coupling member 3, which is supported, by a suitable link or other connecting member, 4, in proximity to an opening, 5^a, of a metallurgical furnace, 5. The hydrocarbon tube is closed 50 at its end farthest from the coupling member, 3, and is open thereinto at its opposite

end, at which it is in continuous communication with a hydrocarbon supply pipe, 1^a. A plurality of conical outwardly tapering delivery passages, 1^b, shown clearly in Fig. 7, 60 are formed in the hydrocarbon tube, 1, extending for a portion of its length from its closed end toward its opposite end. The hydrocarbon tube is maintained in concentric relation to the vaporizing tube, 2, by an interposed spacer or spacers, 1^c.

An ejection nozzle, 1^d, the opening of which is preferably oblong or substantially quadrangular in form, with its longer dimension located horizontally, is formed on, 70 or fixed to, the hydrocarbon tube, at its end farthest from the coupling member. For application in open hearth furnaces, the vertical section of the ejection nozzle may desirably be made tapering inwardly toward 75 the outlet, as shown in Fig. 7, and for other work, as heating ovens, coke ovens, annealing pits, etc., be tapered outwardly, as shown in Fig. 9, so as to produce a wider flame, or one that is less concentrated.

A steam supply pipe, 6, leading from a steam boiler (not shown) extends longitudinally, adjacent to the vaporizing tube, 2, and to or near the ejection nozzle thereof, and after being helically turned into a superheating coil, 6^a, is returned to a connection with the coupling member, 3, through a passage, 6^b, within which, it is continuously in open communication with the vaporizing tube, 2. It may, however, if preferred, 85 as shown in the structural modification, Fig. 6, be connected to the hydrocarbon tube at a point nearer the ejection nozzle thereof.

The hydrocarbon tube and the steam supply pipe are independently controlled by 95 suitable regulating valves 1^e and 6^c, respectively, and it is to be understood that the hydrocarbon tube is to be made of material sufficiently refractory to prevent it from being melted or burned out within an unduly short 100 period of service, and that the hydrocarbon tube is to be extended into the furnace chamber for such length, determined by operative conditions, as may be found desirable for the application of the necessary degree of heat. 105

In the operation of the appliance, the high degree of heat imparted to the steam, in its passage through the steam supply pipe and superheating coil, effects the vaporization of the steam into its constituent elements of hydrogen and oxygen, the heat of which, acting upon the outer surface of the hydrocarbon

tube, vaporizes the hydrocarbon liquid passing through said tube into molecules of its constituents, which escape, in divided currents, through the circumferential delivery 5 passages of the tube, into the surrounding vaporizing tube, within which they meet, and are commingled with the molecules of the decomposed steam. The resultant gas is discharged into the furnace chamber, through 10 the ejection nozzle of the vaporizing tube, and its combustion in the furnace chamber effects the exertion of a high degree of heat therein.

I claim as my invention and desire to secure by Letters Patent:

1. The combination of a block coupling member, provided with passage-ways for hydrocarbon and superheated steam, a relatively long and unobstructed hydrocarbon tube connected to the hydrocarbon passage-way in said block, said tube being provided in its outer end portion with a plurality of circumferential delivery passages, an outer vaporizing tube inclosing and spaced from the hydrocarbon tube, said latter tube being connected at its inner end to the superheated steam passage-way of the block coupling member, and having its outer end terminating in an ejector nozzle, a steam supply pipe extending outside of and in a direction in line with the vaporizing tube, a superheater in the line of the steam supply pipe comprising a coil formed about the outer end of the 25 30 35 40 45 50 55 60 vaporizing tube adjacent the nozzle thereof, means carried by the block coupling member for supporting the burner from without a furnace in operative position and a valve controlled pipe section leading into the steam supply pipe and adapted for connection to a source of steam supply.

JOHN STARK.

CLINTON G. REED,
D. G. STOKES.

vaporizing tube adjacent the nozzle thereof and a valve controlled pipe section leading 35 into the steam supply pipe and adapted for connection to a source of steam supply.

2. The combination of a block coupling member, provided with passage-ways for hydrocarbon and superheated steam, a relatively long and unobstructed hydrocarbon tube connected to the hydrocarbon passage-way in said block, said tube being provided in its outer end portion with a plurality of circumferential delivery passages, an outer vaporizing tube inclosing and spaced from the hydrocarbon tube, said latter tube being connected at its inner end to the superheated steam passage-way of the block coupling member, and having its outer end terminating in an ejector nozzle, a steam supply pipe extending outside of and in a direction in line with the vaporizing tube, a superheater in the line of the steam supply pipe comprising a coil formed about the outer end of the 50 55 60 vaporizing tube adjacent the nozzle thereof, means carried by the block coupling member for supporting the burner from without a furnace in operative position and a valve controlled pipe section leading into the steam supply pipe and adapted for connection to a source of steam supply.
